UNITED STATES PATENT OFFICE.

CHARLES STOLLMERG, OF NEW YORK, N. Y., ASSIGNOR TO AMERICAN CAN COMPANY, OF NEW YORK, N. Y., A CORPORATION OF NEW JERSEY.

CONTAINER.

Application filed February 6, 1922. Serial No. 534,498.

This invention relates to containers, and has more particular reference to the type of container adapted for the packaging of white lead, paint and other heavy materials. 5
5 A principal object of the invention is the provision of an end and body connection in a heavy duty container of unusual strength, and adapted to readily withstand the shocks and jars these containers usually receive in 10 service. It has in contemplation also, the provision for protection of the bottom end seam or connection against damage in service. This is of some considerable importance since these containers are frequently rolled 15 instead of carried.

Numerous other objects and advantages of the invention will be apparent as it is better understood from the following description, which, taken in connection with the accompanying drawings, discloses a preferred embodiment thereof.

Referring to the drawings,

Figure 1 is a side elevation of the container embodying my present invention;

25 Fig. 2 is an enlarged section through the bottom connection; and

Fig. 3 is a similar section, showing the parts in the process of formation.

For the purpose of illustrating my present invention, I have shown on the drawings a container comprising a body 11, to which is secured a bottom 12. While the top of the body forms no part of my present invention, it may be mentioned that it is rolled, preferably upon a wire, into a suitable stiff outstanding construction 13. The bottom is provided with a shoulder 14 fitting within the lower end 15 of the body and is welded thereto throughout the circumference, the 35 zone of welding being indicated by reference character 16. A flange 17 extends outwardly from the shoulder 14 and is curled back upon itself, as indicated in Fig. 2, this curling being preferably to the general configuration of a double seam. That is to say, the metal is bent back upon itself at 18 and the entire structure tightly rolled up, as indicated on the drawing.

By rolling the material of the flange the 40 edge construction at the bottom is stiffened and the weld reinforced, and also, provision is thus made against deformation of the

bottom edge which would interfere with the rolling action when the containers are moved about, it being readily apparent that unevenness of rolling action and the resulting jars in rolling would tend to weaken the weld connection.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container for heavy materials, comprising a sheet metal body wall having a protruding curl at its top, a bottom having a shoulder fitting within the lower end of said body wall and welded thereto, the edge of said bottom being folded upward and thence downward and having its inner part pressed against the outer face of said body wall, the outer part of the flange of the bottom being engaged and braced by the end of said inner part and adapted to cooperate with the said curl at the top to permit the rolling of the container.

2. A container for heavy materials, comprising a sheet metal body wall having a protruding curl at its top, a bottom having a shoulder fitting within the lower end of said body wall and welded thereto, the edge of said bottom being folded upward and thence downward and having its inner part pressed against the outer face of said body wall, the outer part of the flange of the bottom being engaged and braced by the end of said inner part and adapted to cooperate with the said curl at the top to permit the rolling of the container, and a zone of welding formed between the shoulder of the bottom and the body opposite to the upwardly bent flange of the bottom and extending down along the body.

3. A container for heavy contents, having in combination a body formed with a projecting rim at its upper part, a bottom having an inwardly bent and shouldered part fitted within the lower end of the body,

and a flange of the said bottom bent upwardly, inwardly and downwardly with the downwardly bent part against the side of the body opposite to said shoulder.

5. 4. A container for heavy contents, having in combination a body formed with a projecting rim at its upper part, a bottom having an inwardly bent and shouldered part fitted within the lower end of the body,

and a flange of the said bottom bent upwardly, inwardly and downwardly with the downwardly bent part against the side of the body opposite to said shoulder, and a zone of welding formed between the shoulder of the bottom and the body opposite to the upwardly bent flange of the bottom. 10 15

CHARLES STOLBERG.
